UNITED STATES PATENT OFFICE.

LOWELL D. COLE, OF PAINTED POST, NEW YORK.

FENCEPOST.

1,408,723.

Specification of Letters Patent.

Patented Mar. 7, 1922.

Application filed December 5, 1919. Serial No. 342,820.

To all whom it may concern:

Be it known that I, LOWELL D. COLE, a citizen of the United States, residing at Painted Post, in the county of Steuben and 5 State of New York, have invented certain new and useful Improvements in Fenceposts, of which the following is a specification.

This invention relates to a fence post and has for its principle object the production 10 of a fence post which may be easily assembled and taken apart when so desired.

Another object of this invention is to provide a post which has means for receiving wire without the use of nails or staples.

15 A still further object of this invention is the production of simple and efficient means whereby the post may be placed in a substantially vertical position when the fence is being run along somewhat uneven ground.

20 With these and other objects in view, this invention consists of certain novel combinations, arrangements and constructions of parts as will be hereinafter more fully described.

25 In the drawings:

Figure 1 is a side elevation of my device showing same partly broken away.

Figure 2 is a top plan view of the base portion showing the post in section, taken 30 on line 2—2 of Figure 1 looking in the direction of the arrow, and

Figure 3 is a section taken approximately on the line 3—3 of Figure 2 looking in the direction of the arrows.

35 By referring to the accompanying drawings by numerals it will be seen that 1 designates the post upon which is provided the clamping member 2 by means of the bolt 5 and nut 6. Upon the upper end of the post 40 1 there is mounted the extension 3 by means of nails (not shown) or in any other suitable manner which extends at an oblique angle to the post 1. This extension 3 has a clamping member 4 which is attached to the 45 extension by means of the bolt 5 and nut 6.

The post 1 is carried by a base mechanism which will be now described. This base mechanism consists of the parallel base arms 9 which are provided with slots for receiving 50 the parallel base arms 10 which extend at right angles thereto. The base arms 10 are provided with slots in their bottom edges so as to register with the slots provided in the base arms 9. A block 16 is placed in 55 the center of the base arms as is clearly shown in Figure 2 of the drawing and holds

them in a spaced relation to each other. This block is held in place by means of the bolt and nut 15. Mounted between the base arms 9 and 10 are base bars 11 which are held between the arms 9 and the arms 10 by means of the bolts 14'. The base bars 11 are provided at their free ends with the beveled portions 12. Each beveled portion 12 has an opening 13 therein. The opening 13 is 60 adapted to receive a spike 14 for holding the base mechanism in engagement with the ground. The upright standards 7 are attached to the block 16 by means of the bolt 15 and extend between the base arms 10 as 65 clearly shown in Figures 2 and 3 of the drawing. The post 1 is held between the upright standards 7 by means of the bolts 8 and nuts 9.

70 From the above description it will be seen that each part of this fence post may be easily disassembled or assembled. It will also be seen that by removal of the proper ones of the bolts 14' the base bars become pivotally mounted within the base arms, so 75 that when the device is to be used upon uneven ground the post 1 may be extended in a substantially vertical position by an adjustment of a base bar when one of the bolts 14' is removed. It will also be understood 80 by removal of one of the bolts 8 the post 1 will pivot between the standards 7, and also, that chicken wire or some such similar fencing material may be held in engagement with the post by means of the clamping 85 members 2 and 4. It will also be noted that after the desired arms 11 are each swung on one of their bolts 14', after the other is removed, each of the arms may then be held in an adjusted position by tightening the 90 nut on the bolt that has served as a pivot.

95 The drawing and description above relate to what I might call the preferred form of my invention and I wish it understood that I may make such changes in arrangement 100 and combination and constructions as fall within the scope of the appended claims.

Having thus described my invention, what I claim as new is:—

1. A device of the class described comprising a block, fixed base arms attached to the block, adjustable base bars mounted upon said fixed arms, and means provided for holding said bars in engagement with the ground. 105
2. A device of the class described comprising a block, a plurality of base arms attached 110

to the block so as to extend along the ground, adjustable base bars carried by the base arms and provided with beveled terminals having openings extending at right angles therethrough, and spikes passing through the openings.

3. A device of the class described comprising a block, a plurality of base arms arranged in pairs attached to the block, ad-

justable base bars carried between the base arms and means provided for holding the bars in engagement with the ground.

In testimony whereof I affix my signature in presence of two witnesses.

LOWELL D. COLE.
